MOUNTING FOR BAIL HANDLES

Howard V. Stehl, Woodlawn, Md., assignor to
Rheem Manufacturing Company, New York,
N. Y., a corporation of California

Application January 20, 1945, Serial No. 573,775

4 Claims. (Cl. 16—126)

1

The invention relates to handles for porting objects and packages and particularly anti-personnel and anti-tank mines and the like.

It has for an object to present a novel construction in the manner of mounting the handle in relation to a special form of the article and the relation of its center of gravity to the handle mount so that the article will hang from the handle, when ported, nearly in a vertical plane.

A further object is to simplify and cheapen the production of a device having the advantages mentioned and others, as will appear.

It is an important aim of the invention to enable the inclusion of a handle with ample width of hand grip in a recessed part, where the shape of the recess available precludes the use of the handle in conventional ways.

Additional objects, advantages, and features of the invention reside in the construction, arrangement and combination of parts involved in the embodiment of the invention as will be more readily apparent from the following description and accompanying drawings, wherein:

Figure 1 is a bottom view of a mine embodying the invention, the handle packed;

Figure 2 is a fragmentary similar view, the handle in use;

Figure 3 is a radial fragmentary section of the handle and mount in packed condition;

Figure 4 is a similar view showing the handle extended.

Referring more particularly to the drawings, there is illustrated a mine 10 having a main bursting charge container 11 of sheet metal, having a generally circular form and including a bottom plate 12 secured to the circular wall part 13 conventionally. On account of the nature of the explosive in the container being such that it is rigid after introduction into the container, the material of the bottom plate does not require great strength, but in order to insure adequately dependable permanence of form of the receptacle before loading while yet using extremely thin sheet material, the bottom 12 is pressed to a form with impressed quadrant areas 14 leaving raised radial ribs or spokes 15 of spider form by which the bottom is stiffened adequately. The spaces 14 are of sufficient depth to accommodate a handle material of adequate thickness, and a novel attachment for a handle is presented, in order that the handle grip with adequate width may be pivoted in this space, yet so connected to the mine when swung outward that the pivot will be at a maximum practicable distance from the center of gravity of the mine.

The spoke portions 15 are formed as continuations from a central generally circular raised hub part 16. In the generally quadrant shaped depressed area 14 between two spokes, a radially arranged strap guide, clamp and anchorage 17 is provided. This consists of an elongated gen-

2

erally rectangular and planiform blank of sheet metal similar to that in the plate 12, having opposite lateral ear extensions 18 at one end, its opposite end portion being curved at right angles as at 19 around an axis transverse to the length of the blank to form a leg part, and then bent abruptly outwardly at right angles on a transverse line 20 to form an offset foot flange 21 in a plane parallel to the body of the blank at a distance approximately the depth of the quadrant recess 14 or less.

The opposite end portion of the blank is bent inward as at 22 around an axis transverse to the blank so that the outer and lower part of the blank extends longitudinally inward at an oblique angle as a leg 23 and then bent sharply inward longitudinally on a transverse line so that the extreme end portion of the blank including the ears 18 lies under and parallel to the body of the blank, forming an anchor foot 24, in a plane with the foot flange 21. The bend 22 in the recurved part is made with a very short radius around an axis spaced nearer the upper planiform guide body part 25 of the anchor, for receiving and releasably holding a handle bail by snap action as will be explained.

The foot flange 21 is provided with two or more dimples 26, and similar dimples 27 are formed in the ears 18 at the opposite side of the material so that high points are provided next to the material of the bottom plate 12 when the anchor is set in place for projection welding.

The anchor-guide-retainer clamp 17 so formed is set in place in the recess 14 with the foot pieces 35 against the bottom plate 12, the foot flange being immediately adjacent the hub part 16, and the longitudinal axis of the blank being radially disposed in equiangular relation to the spoke ribs 15, and it is then secured by conventional projection welding at the dimples.

A bail handle 28 is provided, which may generally conform in plan to the shape of the space 14. It thus includes the wide curved grip portion 28', inturned side arms 29 convergent toward their inner or lower ends, and a rectilinear pivot bar portion 30 connecting the proximal part of the arms 29. This handle is formed of heavy wire bent at the junction of the parts of the handle last above named, the bends being preferably so located that the ends of the wire blank fall in one of the side arms 29 where they may be butt welded together as at 31. The diameter of this wire is less than the space between the anchor foot 24 and body 25 of the anchor and the pivot bar 30 is arranged transversely under the guide body before the anchor is welded in place.

The recurved end of the anchor is spaced from the outer side of the quadrant recess 14, sufficiently to accommodate a portion of the wire of the bail grip 28' outwardly of and below or

inward of the shoulder 32 formed by the recurved part 24, and the radius of the grip portion 28 on each side of the medial radius from the hub 16 through the blank is sufficiently less than the measurement from the pivot bar 30 to the shoulder 32 to require the bail to be sprung slightly outward in order to pass the shoulder when the pivot bar is immediately adjacent the foot flange 21. In order to hold the pivot bar manually releasably adjacent the foot flange, a transverse depression forming a wiper 34 is provided across the guide body near the leg 19, rounded so that while translation of the pivot bar longitudinally under the guide is opposed sufficiently to permit the bail grip to be snapped over and under the shoulder 32, a moderate pull or twist of the handle radially of the mine or tending to move a part of the pivot bar longitudinally of the guide away from the leg 19 will start the pivot portion under and past the wiper 34 and the pivot of the bail may be moved radially and slidably under the guide until it engages leg 23.

Preferably the bends at the junctions of the side arms 29 and pivot bar are sharply made, and may be at 70° angles for a distance and the arms then curved outwardly as at 35 so that the bail part may extend over the full radius of the recess 14.

In addition the arms 29 are preferably curved downwardly for a short distance adjacent the pivot bar as at 36, so that the handle is off-set from the mine when the pivot bar is brought to the outer end of the guide.

With the handle in the last described position, when the grip portion is grasped and the mine lifted, the mine being a flat structure, its bottom will swing near to a vertical plane so that it may be ported by a soldier with a minimum interference with his steps in walking when the soldier's arm supporting the mine is allowed to swing by his side.

The construction of the mine in other particulars than those referred to herein including detonating devices and operation means, may conform to any approved practice without impairment in function by the use of my porting handle and its mounting.

When a mine is to be armed and set for offensive action my handle bail pivot bar 30 is moved to the lower or inner end of the guide past the transverse depression 34, and the grip 28 pressed down to snap past the shoulder 32, where it will be held by the shoulder, and will so remain while the mine is set in accordance with conventional practice.

While I have disclosed the invention with particularity in a specific application to use with a mine device, it will nevertheless be understood that this is exemplary and that various modifications may be made of structure and arrangement, substitution of materials and equivalents, mechanical or otherwise, for use in mines or in receptacles or packages generally, with omissions or additions, without departing from the spirit of the invention set forth in the appended claims.

I claim:

1. A carrying device for a portable article having a flat surface thereon, comprising a bail having a hand grip and a pivot bar, a strap secured to and spaced from said surface and defining therewith a slot, said pivot bar being positioned within said slot and movable longitudinally thereof, one end of said strap having a leg directed towards said surface and inclined with relation to said surface to define a shoulder for engaging and releasably holding the said hand

grip; a second leg at the other end of said strap also directed towards said surface, said two legs, said surface and said strap confining said pivot bar within said slot; a depression running transversely of said strap near the end thereof having said second leg and extending sufficiently into said slot to yieldingly hold the said pivot bar between said depression and said second leg when the said pivot bar is moved in said slot past said depression to said second leg, the dimensions of said bail and of said strap being such that when the said pivot bar engages against said second leg, the said hand grip may be sprung over said shoulder to be engaged and releasably held thereby.

2. A handle device for a flat surface container comprising a bail handle having a pivot bar, an inverted substantially U-shaped guide and mount forming with said surface a slot receiving said pivot bar transversely therethrough for translative movement longitudinally in said slot, means formed in said guide at one end of said slot for yieldingly holding the bail at one limit of said movement; a wiper comprising a depression formed transversely in said guide adjacent the opposite end of said slot and directed towards said surface to receive said bail thereagainst to be sprung past said wiper for alternate engagement and release.

3. As an improved article of manufacture a mount for a bail and the like, said mount consisting of an elongated blank of resilient sheet metal having a bail pivot receiving means formed in one end and adapted for attachment to a receptacle, the opposite end being determined at a distance corresponding to the arc of movement of the radially extreme part of said bail and adapted for attachment to a receptacle, said opposite end being formed so as to have a downwardly and inwardly directed portion so as to present a longitudinally projecting shoulder to snapingly engage and releasably hold said bail in parallelism with said mount.

4. A carrying device for a portable receptacle comprising a pair of spaced surfaces defining a slot, a bail having a hand grip and a pivot bar, said pivot bar being positioned in and slidably longitudinally of said slot, a first stop member at one end of said slot and a second stop member at the other end of said slot for confining said pivot bar within said slot, a detent near said first stop member for releasably holding said pivot bar near such first stop member, said second stop member having a surface exteriorly of said slot that inclines inwardly towards said slot to define a shoulder, the dimensions of said bail being such that when the said pivot bar engages against said first stop member, the said hand grip may be sprung over the said shoulder.
